UNITED STATES PATENT OFFICE

2,557,343

PACKING CORD, BEADING CORD, EDGE
ROLL, OR THE LIKEWayne S. Cook, Grand Rapids, Mich., assignor to
Sackner Products, Inc., a corporation of Michigan

Application August 19, 1948, Serial No. 45,123

6 Claims. (Cl. 87—1)

1

This invention relates to improvements in packing cord, beading cord, edge roll or the like.

The main objects of this invention are:

First, to provide a packing cord, beading cord, edge roll or the like which has relatively high tensile strength, is uniform in dimensions, has a smooth exterior and may be economically produced.

Second, to provide a structure of this character which may be produced with minimum waste material.

Further objects relating to details and economies of the invention will appear from the description to follow. The invention is pointed out in the claims.

A preferred embodiment of the invention is illustrated in the accompanying drawings, in which:

Fig. 1 is an enlarged fragmentary view of a packing cord or beading cord embodying my invention the parts being shown mainly in conventional form.

Fig. 2 is a cross sectional view.

Fig. 3 is a fragmentary view illustrating a fragment of a strip of creped cellulose tissue employed in the forming of the body portion of the structure.

Fig. 4 is a conventionalized and enlarged section of a wrapping strand element of my invention.

In the accompanying drawing the parts are shown in conventionalized form owing to the difficulty in illustrating in proper proportions. The product or material of my invention is variously designated as packing cords, beading cords, edge rolls and the like, depending upon the particular use to which it is to be put.

While structures embodying my invention are particularly desirable when used as packing cords or beading cords it should be understood that my invention may be embodied in materials for various uses. A structure of the general character of my invention is illustrated in the Sackner Patent No. 1,821,582, issued September 1, 1931. That patent discloses cords made up of layers of creped sheets or cellulose wadding or tissue paper compressed into cylindrical forms and retained by braided wrapping threads or yarn of cotton.

In the commercial practice of my invention I form an elongated body 1, usually of cylindrical section, from a strip or strips of tissue 2 which is desirably creped and which is crumpled transversely and compressed without twisting into the body. Whether one or more strips are employed depends on the diameter of the body desired. In

2

the preferred embodiment of my invention the body is formed of one or more strips of creped tissue which are compressed and crumpled edge-wise, as is indicated in the Fig. 3, to form the body 1 which can be produced of uniform cross section owing to the fact that the strips of the desired width can be employed and are crumpled and compressed to make up the body.

The body is bound into its formed shape by 10 wrapping strands 3 which are braided thereon in open mesh, closely embracing relation, the strands being partially imbedded in the body. These strands are in the embodiment illustrated of flattened cross section and consist of glass fiber 15 filaments formed into the strand and impregnated and coated with wax preferably micro-crystalline. The coating may be a mixture of a microcrystalline wax and a mineral oil. Micro-crystalline wax as commonly known in commerce 20 refers only to those waxes usually derived from petroleum which are not brittle or coarsely crystalline, but which are actually microcrystalline and ductile or non brittle. Mineral oil may be defined as any oil of mineral origin as petroleum 25 or shale oil or any oil obtained from them by refining. The wax coats and binds the glass fiber filaments together and provides a substantially smooth coating for the strand. This results in a strand having a much greater tensile strength 30 than thread or yarn and also results in a packing or beading cord or edge roll having a very smooth exterior and one of a tensile strength greatly exceeding that of the packing cord of the Sackner patent referred to the increase in tensile strength, 35 particularly in the smaller cords or beadings, being as high as 75%.

A further advantage of the invention is that this superior product may be produced at a 50% reduction in the cost of the wrapping strand as 40 compared to the thread or yarn heretofore used.

Further advantages result from the fact that the strands slide freely through the guides or eyes of the braiding machine and there is no accumulation of lint. The strands may be applied successfully with a considerably greater tension than is possible with the cotton cord or strands commonly used. At the same time, the structure is flexible and resilient. The wrapping strands are not materially weakened when wet and the 45 stretchability is not increased by wetting. While it is not ordinarily contemplated that these packing cords, beading cords, edge rolls and the like should be subjected to any considerable amount of moisture somewhat they are sometimes used 50 in conditions where parts may become wet and 55 in conditions where parts may become wet and

they are affected by humidity conditions and changes. Impregnation and coating the strands with microcrystalline wax is advantageous over ordinary wax or paraffin in that it permits substantial bending and flexing of the strands under substantial tension without fraying or separation of the glass fibers, particularly at the ends thereof, such fraying or separation of the fibers tending to weaken the strands. It holds the fibers of the strands together during production operations, especially where breaks may occur and adapts the cord braided therewith to a wide variety of uses particularly when subject to severe bending or flexing stresses over a considerable period of time. Coating and impregnating the glass strands with the micro crystalline wax, also desirably combines lubrication for passage of the strands through the braider and provides tackiness to hold the yarn on the braider cops and on the final product.

The increased tensile strength of the product permits its being more readily applied and even when undue stress is applied such stress is effectively resisted and it does not objectionably vary the diameter. Rupturing of the body material is minimized owing to the protection afforded by the wrapping or winding strands. After the cord is formed as described it may be shaped into flattened or oval or other cross section and maintains the shape into which it formed.

I would again point out that the drawings are mainly conventionalized and illustrate a practical embodiment of my invention. A structure of the dimension illustrated in Fig. 1 might be used for an edge roll for upholstery and the like. My invention, however, is of particular value when embodied in the smaller packing and edging cords which are produced in large quantities ranging from $\frac{1}{16}$ " to $\frac{1}{2}$ " although there is large production in cords of other diameters. It will be understood that the illustrations are not intended to be in proper proportions either as to the material constituting the body or the fiber glass filaments of the wrapping strand. Instead of using individual strips or sheets of creped tissue the cellulose wadding may be used, this consisting of a plurality of sheets of very thin cellulose tissue more or less interlocked by superimposing one upon another.

It is desired to emphasize that the packing cords, beading cords and the like of this invention have a very smooth surface inasmuch as the relatively fine strands permit braiding with such tension that they are substantially imbedded in the body material of the cord. At the same time, the thread or strand results in a very strong cord or the like. Cotton and other cords commonly used do not become substantially imbedded into the filler or body material and this results in a rough surface particularly where the threads cross each other.

In the applicant's structure the surface is, as stated, substantially smooth throughout. The additional smoothness and additional tensile strength permits the cord material to be pulled easily through a welded seam or the like. Also the applicant's strand is very much less than cotton cords and other strands heretofore used in various relations. The smooth surface has a very decided advantage when the cord is used in connection with sheer or thin materials and it permits plastic coatings and coverings in various embodiments of the cord. This is not practical where cotton threads or cords are used

as the coating with plastic would result in a rough and uneven surface.

The strands may be formed of strands or yarn commercially known as "Fiberglas." I desire to point out, however, that the "Fiberglas" strands without being impregnated and coated with the wax as I have described do not produce a product comparable with the product of my invention.

Having thus described my invention, what I claim as new and desire to secure by Letters Patent is:

1. An article of manufacture of the class described, consisting of a strip of creped cellulose tissue crumpled transversely and compressed without twisting into an elongated substantially cylindrical resilient body, and glass fiber strands wrapped around the compressed cellulose tissue and braided into open mesh closely embracing relation thereto, each strand being composed of

20 a plurality of glass fibers, the strands being impregnated and coated with microcrystalline wax, said strands being embedded in the cellulose tissue to provide a smooth surface, said strands being relatively fine and of substantial tensile

25 strength to facilitate wrapping thereof under substantial tension around the cellulose tissue and the embedding thereof in the cellulose tissue.

2. An article of manufacture of the class described, consisting of a strip of creped cellulose tissue crumpled transversely and compressed into an elongated substantially cylindrical resilient body, and glass fiber strands wrapped around the compressed cellulose tissue and braided into open mesh substantially imbedded relation thereto to provide a smooth surface, each strand being composed of a plurality of glass fibers, the strands being impregnated and coated with microcrystalline wax.

3. A packing cord, beading cord, edge roll or the like, comprising creped cellulose tissue crumpled edgewise and compressed into an elongated body of substantial resilience and uniform section and a wrapping of glass fiber strands of flattened cross section braided in open mesh thereon, each strand being composed of a plurality of glass fibers, the strands being impregnated with microcrystalline wax flexibly binding the fiber glass filaments together and coating the strand, said strands being embedded in the cellulose tissue to provide a smooth surface, said strands being relatively fine and of substantial tensile strength to facilitate wrapping thereof under substantial tension around the cellulose tissue and the embedding thereof in the cellulose tissue.

4. A packing cord, beading cord, edge roll or the like comprising cellulose tissue crumpled and compressed into an elongated body of substantially uniform section and of substantial resilience and a braided wrapping therefor of strand each of glass fibers, said strands being impregnated with a microcrystalline wax and a mineral oil, said strands being embedded in the cellulose tissue to provide a smooth surface, said strands being relatively fine and of substantial tensile strength.

5. A packing cord, edge roll or the like comprising cellulose fiber material conformed into an elongated body of substantial resilience and a uniform section and a wrapping of glass fiber strands braided thereon, each strand being composed of a plurality of glass fibers, the strands being of flattened cross section and impregnated and coated with wax, said strands being disposed

with a flattened side in engaging relation with the compressed cellulose fibers, said wax facilitating conforming and retaining the strands to flattened section.

6. An article of manufacture of the class described, consisting of cellulose tissue crumpled and compressed into an elongated body, and strands of flattened section and of glass fiber wrapped around the compressed tissue and impregnated and coated with wax and braided 10 thereon in open mesh with the strands in closely embracing form retaining relation thereto, said wax facilitating conforming and retaining said strands to flattened section.
